ISRAEL FOSTER, OF PHILADELPHIA, PENNSYLVANIA.

Design No. 3,201, dated September 22, 1868.

DESIGN FOR A CARPET-PATTERN.

The Schedule referred to in these Letters Patent and making part of the same.

TO ALL WHOM IT MAY CONCERN:

Be it known that I, ISRAEL FOSTER, of the city and county of Philadelphia, State of Pennsylvania, have invented or produced a new and original Design for a Carpet-Pattern; and I do hereby declare that the accompanying drawing, and the following explanation thereof, form a full, clear, and exact description of the said design.

The figure in the drawing represents sufficient of a carpet to illustrate the design of the pattern, A being a portion of the body, and B the border of the carpet.

The body is ornamented with figures, of a form clearly indicated in the drawing.

Near the outer edge of the border, is the waved stripe *a*, next to which is the rib *b*, and next the stripe *c*, all being on dark ground.

Next to the ornament *d*, the form of which is clearly shown, are arranged the stripes *e* and *f*, on a dark ground, which unites with the body.

Irrespective of the colors employed, I claim—

The design for a carpet-pattern, substantially as described, and represented in and by the accompanying drawing.

In testimony whereof, I have signed my name to this specification in the presence of two subscribing witnesses.

ISRAEL FOSTER.
